UNITED STATES PATENT OFFICE.

SATISH CHANDRA GHOSH, OF CHICAGO, ILLINOIS.

INCENSE BURNER.

1,412,516.

Specification of Letters Patent. Patented Apr. 11, 1922.

Application filed May 3, 1920. Serial No. 378,624.

To all whom it may concern:

Be it known that I, SATISH CHANDRA GHOSH, a subject of the King of Great Britain, and a resident of the city of Chicago, 5 county of Cook, and State of Illinois, have invented certain new and useful Improvements in Incense Burners, of which the following is a specification.

My invention relates to improvements in 10 incense burners, and has for its object the provision of an improved construction of this character which is of simple construction and efficient in use.

Other objects will appear hereinafter.

15 The invention consists in the combinations and arrangements of parts hereinafter described and claimed.

The invention will be best understood by reference to the accompanying drawings 20 forming a part of this specification, and in which,

Fig. 1, is a side view of a burner embodying the invention, and,

Fig. 2, a top plan view of the same.

25 The preferred form of construction, as illustrated in the drawings, comprises a flat metallic base plate 3 in the form of a leaf and having a loop 4 struck upwardly from one side thereof. A supporting stem 5 has its 30 lower end secured under said loop, said stem being curved upwardly and inwardly therefrom and provided with a burner socket at its upper end. This socket consists of a base 5' in the form of a disc secured to the upper 35 end of the stem 5, and having plates 6 extending upwardly and outwardly therefrom to form recesses 7 between said plates, said plates 6 being substantially in the form of the petals of a flower, as indicated.

40 By this arrangement, a simple and effective device for the purpose is provided which is capable of economical manufacture. The recesses 7 formed in the sides of the burner admit air to the interior thereof which facilitates the burning of the incense and the resulting smoke rising centrally therefrom

gives the appearance of smoke flowing out of a flower.

While I have illustrated and described the preferred form of construction for carrying my invention into effect, this is capable of 50 variation and modification without departing from the spirit of the invention. I, therefore, do not wish to be limited to the precise details of construction set forth, but 55 desire to avail myself of such variations and modifications as come within the scope of the appended claims.

Having described my invention, what I claim as new and desire to secure by Letters 60 Patent is:—

1. In an incense burning stand having a flat base; a loop at one side of said base; a stem having a curved end adapted to be inserted in said loop to hold same in upright position; said stem having an inward and upward curve to position the upper end of said stem over the center of said base to prevent tilting thereof; and a receptacle on the end of said stem for supporting burning 70 incense, substantially as described.

2. In an incense burning stand having a flat base; a loop at one side of said base; a stem having a curved end adapted to be inserted in said loop and frictionally engage 75 therein to hold same in upright position; a stem having an inward and upward curve to position the upper end of said stem over the center of said base to prevent tilting thereof; a receptacle on the end of said stem 80 for supporting burning incense; and various openings in said receptacle to permit the issuance of smoke from the burning incense, substantially as described.

In testimony whereof I have signed my 85 name to this specification in the presence of two subscribing witnesses.

SATISH CHANDRA GHOSH.
